OIL BURNING APPARATUS

William J. Smith and William W. Slaght, Rocky River, Ohio, assignors to Cleveland Steel Products Corp., Cleveland, Ohio, a corporation of Ohio

Application September 25, 1939, Serial No. 296,508

3 Claims. (Cl. 158—4)

This invention relates to oil burning apparatus, more particularly to oil burning apparatus of the wall-flame type.

In oil burning apparatus of the wall-flame type, oil and air are discharged horizontally from a rotatable distributing head above a hearth member into contact with a combustion promoting structure located near the furnace walls, which includes an oil vaporizing wall. It is customary to also employ a number of vapor or flame directing members associated with the combustion promoting structure to assist in the placement of the flame of combustion at the desired location.

One of the objects of the present invention is to provide a new and improved hearth and combustion promoting structure for wall flame burners which is economical to manufacture and easy to install and which is efficient in operation.

Another object is to provide oil burning apparatus of the wall flame type with improved and efficient means for associating vapor and flame directing members with the combustion promoting structure.

A further object is to provide new and efficient ignition means for use in oil burning apparatus of the wall flame type.

A further object is to provide an improved means for associating the air and oil distributing means of a wall flame burner with the hearth structure thereof.

With the above and other objects in view, the present invention consists in certain features of construction and combinations of parts to be hereinafter described with reference to the accompanying drawings and then claimed.

In the drawings which illustrate a suitable embodiment of the invention Figure 1 is a horizontal section taken through a furnace structure looking downwardly upon oil burning apparatus of the present invention installed therein;

Figure 2 is a vertical section taken approximately on line 2—2 of Figure 1;

Figure 3 is a vertical section taken on line 3—3 of Figure 1 showing the ignition means;

Figure 4 is a vertical section taken on line 4—4 of Figure 1 showing the air inlet opening; and

Figure 5 is a perspective view of one of the vapor and flame deflecting members.

Referring to the accompanying drawings in which like numerals refer to like parts throughout the several views, we have shown a boiler or hot water heater comprising an annular base

plate 10 secured by welding or other suitable means to a cylindrical supporting member 11 below the upper edge thereof as shown in Figure 2. Secured by welding to the plate 10 at its inner periphery is an inner cylindrical shell 12 and secured by welding to the plate 10 intermediate its peripheral edges is an outer cylindrical shell 13, the shells 12 and 13 forming the water space. The shell 13 is surrounded by suitable insulation material 14 held in place by an enclosing shell 15.

The cylindrical supporting member 11 is provided with an opening 16 through its wall and associated with this opening is a frame 17 which carries a screen or similar grill work 18 to permit air to flow into the supporting member 11. The frame 17 is secured over the opening 16 by means of screws 19.

Heretofore, it has been the practice to provide a built-up hearth and combustion promoting structure for wall flame burners comprising a large number of pieces or parts of different kinds of material.

In the structure of the present invention we have provided a single piece annular casting 20 preferably containing sufficient chromium and nickel to render it capable of withstanding high temperatures and of having long life without being affected by high temperatures. The casting 20 includes a flat circular portion 21 arranged to fit within the inner shell 12 and having its peripheral edge offset to provide a flange 22 disposed to abut the under side of the base plate 10. The flange 22 is provided with radial bifurcated portions 24 arranged to receive studs 23 extending downwardly from the base plate 10 so that the casting can be clamped in position by means of nuts 25, as shown in Figure 2. Preferably the upper side of the flange 22 is formed with a circular groove 26 to receive a packing 27 which is compressed when the flange 22 is in clamped position to prevent air flow between the flange 22 and base plate 10.

The casting 20 divides the structure into a lower chamber 28 and an upper or combustion chamber 29.

The casting 20 also includes an inner upwardly extending annular flange 30 which provides an air collar, the function of which will be presently described. Within this air collar the flat plate portion 21 is provided with a series of circularly spaced air ports 31 which surround a central aperture 32. Associated with the air ports 31 is a flat air gate 33 having similarly arranged ports 34. The gate 33 is rotatably supported

with respect to the ports 31 by means of a flanged sleeve 35 which extends upwardly through the aperture 32 and is provided with a nut 36 threaded on its upper end and seating on the upper side of the casting portion 21. By rotating the air gate 33 the amount of air flowing through the air ports 31 can be adjusted.

Extending downwardly from the under side of the casting portion 21 are boss-like elements 37 to which brackets 38 are secured by means of screws 39.

The burner motor 40 is provided with slotted radial arms 41 through which cap screws 42 extend, which screws are threaded into the brackets 38. The brackets 38 also carry vertical screws 43 provided with adjusting nuts 44. The screws 43 abut the radial arms 41 for vertical adjustment of the motor 40.

The shaft 45 of the motor is tubular and projects at each end beyond the motor. The upper end of the shaft 45 is threaded and extends within the sleeve 35 and to this end a head member 46 is threaded. Extending from the head member 46 are a plurality of radial oil tubes 47 that open at their inner ends into a recess or chamber 48 within the head member which chamber communicates with the bore of the shaft 45.

The upper end of the head member 46 carries, by means of nut 49, a circular plate 50 having a plurality of fan blades 51 secured to its under side. As shown in Figure 2, the radial oil tubes 47 and fan blades 51 are disposed above the edge of the air collar 30.

In previous constructions it has been the practice to provide a separate air collar which was attached to or abutted against the hearth structure and the motor was attached to or supported from the air collar. In the present construction the construction has been greatly simplified by forming the air collar and air ports as an integral part of the hearth casting 20.

The lower end of the shaft 45 carries a pump member 52 which is formed with threads 53 and surrounded by a cup-shaped casing 54 secured by cap screws 55 to the motor casing, the threads 53 having running engagement with the inner wall of the casing 54 so that as oil feeds through the inlet passage 56 to the open end of the shaft 45 the threading action thereof will cause the oil to flow upwardly through the shaft 45 to the chamber 48 where it is thrown outwardly through the radial tubes 47 in a horizontal direction toward the combustion promoting structure.

The combustion promoting structure comprises a vaporizing element and an air deflecting element. The vaporizing element comprises a continuous ring 58 formed as an integral part of the hearth portion 21 and extending upwardly therefrom to a plane above the oil discharge tubes 47 so that during the operation of the burner the oil discharged horizontally by the tubes 47 will be intercepted by the vaporizing ring 58.

The air deflecting element likewise comprises a substantially continuous ring 59 formed as an integral part of and extending upwardly from the hearth portion 21 to substantially the horizontal plane of the upper end of the air collar 30 as shown in Figure 2.

Arranged outwardly of the vaporizing ring 58 are a number of upstanding deflector supports 60 formed integrally with the hearth portion 21. These supports carry deflecting members 61.

Although different types of deflecting members may be employed, there are shown here, for

illustration, deflectors comprising a flat imperforate plate 62 of heat resistant sheet metal having secured thereto by welding a number of finger strips 63 of sheet metal which extend at an angle to the flat surface of the plate 62. Also secured to the plate 62 and extending in the direction of the strips 63 is a sheet metal strip 64 having tab-like portions 65 at its outer end bent to form a hollow clip 66 for disposition on one of the supports 60 as shown in Figure 2. It is to be noted that in its supported position the plate 62 is supported on the support 60 at an angle above the vaporizing ring 58 to overhang the space between it and the deflecting ring 59, and that the finger strips 63 project downwardly and outwardly beyond the vaporizing ring 60.

The plates 62 may be of any desired length to provide spaces therebetween or if desired they may substantially abut each other to form a substantially continuous imperforate deflecting surface.

In order to minimize the transfer of heat from the combustion chamber 29 to the motor compartment suitable heat insulating material 67 may be provided on the hearth plate 21 between the air collar 30 and deflecting ring 59, between the rings 58 and 59 and between the ring 58 and supports 60. The top surface of the insulating material 67 is somewhat below the upper edge of the deflecting ring 59, as shown in Figure 2.

For ignition there is provided an electric igniter constituting an electrode 68 having its lower portion housed within an insulator 69 mounted within an insulator block 70. The block 70 is disposed within a recess 71 in the hearth portion 21 adjacent the vaporizing ring 58 with the insulator 69, projecting downwardly through an opening 72, as shown in Figure 3. The electrode 68 is doubled back upon itself and then bent outwardly so that its tip points toward and is spaced slightly from the inner wall of the vaporizing ring 58 as shown in Figures 1 and 3.

Supported upon the ring 58 is a short thin plate 73 of heat resistant material which is also an electrical conductor and is capable of rapid heating. This plate 73 and the ring 58 constitutes the other electrode of the igniter. The plate 73 is formed with integral hook-like portions 74 at its upper edge which support it upon the ring 58.

The deflecting ring is broken away adjacent the igniter to provide a short open space 75 for a purpose to be presently described.

With respect to the operation of the oil burning apparatus described, when there is a demand for heat, i. e. burner operation, the control apparatus (not shown) establishes a circuit through the motor 40. The hot spark passing between the electrode 68 and thin plate 73 causes an almost instantaneous heating of the plate. Upon the establishment of the circuit through the motor 40, the motor operates and through the fan blades 50 causes air to be drawn through the controlled ports 31 and discharged horizontally toward the rings 58 and 59, a small portion of the air passes directly over the ring 59 and the remainder is deflected upwardly toward the top of the wall 58 by the ring 59. Simultaneously therewith the oil supply tubes 47 throw horizontal streams of oil outwardly above the hearth and above the deflecting wall 59 into impingement with the vaporizing wall 58 and ignition plate 73 where due to the heating up of the plate 73 and the spark produced by the igniter the oil at that region is ignited. The burning of the

oil at this region causes further and more rapid heating of the ignition plate 13 whereby vaporization and combustion occur. This together with the burning of the oil at the ring 58 causes the metal ring 58 to become heated relatively rapidly with the result that within a very short time all of the oil impinging against the ring 58 is being vaporized and mixed with the air. The deflectors 61 cause the rising mixture to flow outwardly over the ring 58 and combustion occurs adjacent the space between ring 58 and wall 12, the finger strips 63 serving to cause thorough mixing and great turbulence and also to tend to hold the resulting flame down adjacent this space.

Heretofore it has been the practice to support the deflecting members by spaced supports directly on the vaporizing ring. In accordance with the present invention the deflecting members 61 are supported on the supports 60 outwardly of the vaporizing ring 58 thus leaving the upper edge of the ring 58 free of obstructions of any kind so that the vaporized oil may freely travel over the ring without interference from obstructions as was the case in the burners herebefore known.

The correct placement of the oil with respect to the vaporizing wall or ring 58 is easily obtained through the medium of the adjusting screws 43 which when rotated will raise or lower the oil tubes 47. After the correct vertical position of the tubes 47 is obtained, the screws 42 are tightened to lock the motor 40 in position.

Various changes and modifications may be made in the structure shown and described without departing from the spirit of the present invention, as defined by the appended claims.

What we claim is:

1. In an oil burning apparatus of the wall flame type having a combustion chamber provided with an upright wall, and a hearth member forming the bottom of said combustion chamber and having an annular vaporizing wall associated therewith in continuously spaced relation with respect to said upright wall, a plurality of deflecting members disposed above said vaporizing wall and extending inwardly beyond said vaporizing wall, and independent means situated outward-

ly of said vaporizing wall in the space between said latter wall and said upright wall for supporting said deflecting members in spaced relation above said vaporizing wall whereby to provide a completely unobstructed space between said vaporizing wall and said deflecting members.

2. In an oil burning apparatus of the rotary wall flame type having a combustion chamber provided with an upright wall, a metallic hearth member forming the bottom of said combustion chamber and an annular vaporizing wall associated with said hearth member in spaced relation with respect to said upright wall, a plurality of plate-like deflecting members above said vaporizing wall and extending inwardly beyond said wall, and a plurality of spaced elements integral with and projecting upwardly from said hearth member in the space between said upright and vaporizing walls, each of said spaced elements supporting one of said deflecting members behind said vaporizing wall independently thereof in spaced unobstructed relation with respect to the upper edge of said vaporizing wall.

3. In an oil burning apparatus of the rotary wall flame type having a combustion chamber provided with an upright wall, a metallic hearth member forming the bottom of said combustion chamber and an annular vaporizing wall associated with said hearth member in spaced relation with respect to said upright wall, a plurality of plate-like deflecting members above said vaporizing wall and extending inwardly beyond said wall, and a plurality of spaced elements integral with and projecting upwardly from said hearth member in the space between said upright and vaporizing walls, each of said spaced elements supporting one of said deflecting members from behind said vaporizing wall independently thereof in spaced unobstructed relation with respect to the upper edge of said vaporizing wall, said spaced elements and said deflecting members having male and female parts for easy placement of said deflecting members in operative position.

WILLIAM J. SMITH.

WILLIAM W. SLAGHT.
